UNITED STATES PATENT OFFICE.

LEONARD E. HINKLEY, OF MILLERSBURG, OHIO.

BRAKE-SHOE.

1,117,048.

Specification of Letters Patent. Patented Nov. 10, 1914.

Application filed December 2, 1913. Serial No. 804,184.

To all whom it may concern:

Be it known that I, LEONARD E. HINKLEY, a citizen of the United States, and a resident of Millersburg, in the county of Holmes and State of Ohio, have invented new and useful Improvements in Brake-Shoes, of which the following is a full, clear, and exact description.

The invention relates to the wearing blocks or shoes used upon railway brakes, and its object is to provide certain new and useful improvements in brake shoes whereby the steel back and the cast iron body are fused together at all points of contact to prevent the parts from becoming separated when the brake shoe is in use. In order to accomplish the desired result, use is made of a cast metal body provided at its middle with spaced lugs, a steel back cast in the said body and provided with flanges cast into the said body lugs, and a steel loop extending across the said lugs and having its terminals cast into the said lugs. Use is also made of a coating of fusible metal for the said reinforcing steel back and the said loop to fuse the several parts together when casting the body of the brake shoe.

A practical embodiment of the invention is represented in the accompanying drawings forming a part of this specification, in which similar characters of reference indicate corresponding parts in all the views.

Figure 1 is a sectional side elevation of the brake shoe; Fig. 2 is a similar view of the steel back with part shown in section; Fig. 3 is a plan view of the same; Fig. 4 is an enlarged cross section of the brake shoe back and the loop in position in the mold prior to pouring the molten metal for forming the body of the brake shoe; and Fig. 5 is an enlarged cross section of the brake shoe showing the back of the loop embedded in the body and fused thereto.

As shown in Figs. 1 and 5, the body A of the brake shoe or wearing block has embedded in its back portion a reinforcing back B, preferably of steel, and provided near the ends with openings B'. The body A is provided at the middle of its back with spaced lugs A' and the reinforcing back B is provided at its middle with a reduced portion B² from which extend upwardly and outwardly inclined flanges B³ embedded in the lugs A', as plainly indicated in Fig. 5.

5 A loop C, preferably of steel, extends across the lugs A' to form a seat for the key, and

the loop C is provided with inwardly-extending inclined flanges C' embedded in the lugs A' and in portions of the body A. By reference to Fig. 5 it will be noticed that the flanges C' are spaced from and are arranged outside of the flanges B³ of the reinforcing back B² to provide an exceedingly strong reinforced seat for the key. In order to insure a fusing of the back B and the loop C in the cast metal of the body A, the said parts are provided with coatings D and D', of a fusible metal, prior to placing the back B and the loop C into the mold into which the molten metal for the body A is to be poured with a view to embed the back B and the loop C and to fuse the parts together by the coatings D and D' of fusible metal. By reference to Fig. 4 it will be noticed that the mold E is provided with cores F, F' for forming the spaced lugs A' on the body A.

From the foregoing it will be seen that by the arrangement described, the parts are very firmly united to prevent detachment of any one of the parts without the total destruction of the same.

Having thus described my invention, I claim as new and desire to secure by Letters Patent:

1. As an article of manufacture, a brake shoe having a cast metal body provided with central spaced lugs and reinforcing and supporting members both of which members are provided with angular flanges wholly embedded in the said lugs and body, for the purpose described.

2. As an article of manufacture, a brake shoe having a ferreous body formed with central spaced lugs and reinforcing and supporting members having angular flanges wholly embedded in the said lugs and body and having their surfaces coated with a fusible material, whereby the parts may be firmly united without the application of force or pressure.

3. As an article of manufacture, a brake shoe having a ferreous body provided with central spaced lugs and a loop extending across the space between the lugs within the outer limits of the body, the end portions of the loop body being extended laterally into the lugs and being provided with flanges in the said lugs and projecting toward and into the body, all for the purpose described.

4. As an article of manufacture, a brake shoe having in its body a steel reinforcing

and supporting means coated with a fusible metal and cast into the said body, the said coating serving to fuse the body and the reinforcing and supporting means together.

5. As an article of manufacture, a brake shoe having a cast metal body, a reinforcing back of steel embedded in the said body, a key lug having its terminals embedded in the said body, and coatings of fusible metal 10 for the said back and lug to fuse the same to the body.

6. As an article of manufacture, a brake shoe having a ferreous body and reinforcing

and supporting inserts having both their inner and outer surfaces coated with a fusible metal whereby the inserts and body may be firmly united without the application of force or pressure. 15

In testimony whereof I have signed my name to this specification in the presence of 20 two subscribing witnesses.

LEONARD E. HINKLEY.
